UNITED STATES PATENT OFFICE.

JAMES G. SMITH AND HIRAM E. BUTLER, OF JAMESTOWN, NEW YORK.

COMBINED BLACKBOARD AND DESK.

SPECIFICATION forming part of Letters Patent No. 328,727, dated October 20, 1885.

Application filed May 22, 1885. Serial No. 166,344. (No model.)

To all whom it may concern:

Be it known that we, JAMES G. SMITH and HIRAM E. BUTLER, both residents of Jamestown, in the county of Chautauqua and State 5 of New York, have invented certain new and useful Improvements in a Combined Desk and Blackboard, of which the following is a full, clear, and exact description.

This invention more particularly relates to 10 combined desks and blackboards for use in schools and elsewhere, and in which a copy-sheet, preferably of a band description, carried by rollers, and adjustable to expose different "sets" or heads of copy, is combined with the 15 blackboard.

The invention consists in certain novel constructions and combinations of parts, substantially as herein shown and described, and whereby the combined article when open 20 may be used as a writing-desk and when closed as a blackboard, the said board forming also the table to the desk when open and front or door of the desk when closed. Furthermore, the portion carrying the copy-sheet is made 25 to occupy or capable of adjustment into a forwardly-inclining position in an upward direction, so as to form an obtuse angle to the blackboard when closed, whereby the writing or delineations on the copy-sheet are brought 30 within the focus of the eye of the person using the blackboard and desk.

Reference is to be had to the accompanying drawings, forming a part of this specification, in which similar letters of reference indicate 35 corresponding parts in all the figures.

Figure 1 represents a face view of the combined article; Fig. 2, a side or edge view of the same; Fig. 3, a vertical section of the same on the line *x* *x* in Fig. 1, with the copy- 40 sheet frame or holder set inclining in relation with the blackboard, and Fig. 4 a face view of the combined article when open for use as a writing-desk.

A *A* are the side frame-pieces of the structure, and B its back, which latter may have 45 key-notch apertures *b* *b* in it for hanging it upon nails or screws *c* *c* against the wall or on an easel; or it may be stood upon an ordinary table or other stand, and when used as a black- 50 board it may be held upon the lap of a person sitting, with its back resting against the table. Its back is provided on its face with shelves

or partitions to form compartments *d* within the desk for various writing or marking articles or materials used in connection with the 55 desk and blackboard.

C is the combined blackboard and desk table, pivoted below, as at *e* *e*, to the main frame, its outer surface, *f*, serving, when the board is closed, as shown in Figs. 1, 2, and 3, as the 60 marking or drawing surface of the blackboard, and its opposite surface, *g*, when the board is thrown or let down, as shown in Fig. 4 and in part by dotted lines in Fig. 2, as the writing, &c., surface of the desk. When thrown up 65 or closed, as shown in Figs. 1, 2, and 3, the board C, which may be made of either wood or metal, as may also other parts of the structure, and which has or may have a side piece or strip, *v*, on opposite sides of it, serves as a 70 lid or door to the desk, and it may be held closed either by a button, by a spring, *h*, on either side of it, bearing against the side pieces of the main frame, or by any other suitable fastenings.

At the base of the main frame is a receptacle, *i*, to catch the dust and small particles of chalk and crayon that may fall when the article is being used as a blackboard. When the board C is closed, it may rest against a stop, *k*, 80 on either side of the main frame, and when opened or thrown down for use as a desk, writing, &c., table, it may rest at the proper angle on steps or stops *l*.

The whole structure, it will be seen, is composed, mainly, of two leading members—that is, a back or desk-body portion and a blackboard portion, that serves as the table portion of the desk and lid or cover of the body part thereof. When closed it forms a flat, light, 90 and convenient or portable structure suitable for manipulation or use under various circumstances and in different positions.

D is the copy-sheet, which is in the form of a flexible strip, having any number and description of copy-heads or copies upon it, and which is attached at its opposite ends to upper and lower rollers, *m* *n*, carried by a frame, E, consisting of side pieces, *o* *o*, united by a face-piece, *s*, over which, by rotating one or other 100 of the rollers, the copy-sheet is moved and exposed as required, as in other band copy-sheets for the same purpose; but in the present instance the frame E, carrying the copy-

sheet and its rollers, is fitted to rock upon or from its bottom roller-axis into a forwardly-inclining position in an upward direction, so that the exposed copy-sheet will form an obtuse angle to the blackboard when closed, as shown in Fig. 3, whereby the writing or delineations on the copy-sheet will be better seen by being brought within the focus of the eye of the person using the blackboard or desk.

10 The frame E, carrying the adjustable copy-sheet, and which is fitted to rock on the side pieces, A A, of the main frame, may be arrested in its forward pitch by the lower ends of its sides striking the back of the desk, and when 15 said frame E is set back again into line with the body of the desk, as shown in Fig. 2, for the convenience of stowing away or transporting the article, it may be locked, if desired, by a side pin, u, or otherwise.

20 When the lid or cover is folded down at an inclination to the body, so as to present the inner face of the cover uppermost, then a desk-surface for a person to write upon is formed, similar to that of the hinged front of a book-25 case desk in use. The structure is then converted into a desk, and may be suspended from screws, nails, or hooks on the wall of a room, as described, so that a person can stand when engaged in writing, as in case of standing desks generally; or it may be placed upon a person's lap with the back of the body resting against a table-edge; or it may be placed 30 on a table with the flat under side of the receptacle i resting on the top of the table, and

the body A B in an upright position, and the 35 hinged lid or cover in its folded-down position at an inclination to said body.

Having thus fully described our invention, we claim as new and desire to secure by Letters Patent—

40 1. A combined desk and blackboard consisting of the vertical desk-body, the blackboard and desk-lid C, hinged at its lower end to the sides of the body to close the desk and form a blackboard and writing-table, and a 45 copy-holder pivoted between the upper ends of the sides of the desk-body, and adapted to be inclined forwardly over the blackboard or held in the vertical plane of the desk-body, substantially as set forth.

50 2. The combination, with the desk-body having compartments d within it, of the combined blackboard, writing-table, and desk-lid C, pivoted below to the desk-body, and the rocking copy-sheet-carrying frame E, having 55 sheet-carrying rollers m n, and capable of adjustment to occupy a straight or inclined position in relation with the blackboard when closed, essentially as described.
